SOLARIUM

Mike Tecton, 5101 45th St. NW., Washington, D.C.

Filed Mar. 10, 1965, Ser. No. 84,196

Term of patent 14 years

(Cl. D83—1)

FIG. 1

FIG. 2

FIG. 3

FIG. 4

FIG. 1 is a side perspective view showing my solarium;
FIG. 2 is a right side elevational view thereof;
FIG. 3 is a rear elevational view thereof;

FIG. 4 is a top plan view thereof;

The characteristic feature of the design resides in the combination of a domed roof, downwardly sloping sides, one side being sloped and extended beyond the circumference of the bottom of the domed solarium.

I claim:

The ornamental design for a solarium, substantially as shown and described.
